UNITED STATES PATENT OFFICE.

WILLIAM H. JACKSON, OF FALL RIVER, MASSACHUSETTS, ASSIGNOR TO
JAMES MARSHALL & BROTHERS, OF SAME PLACE.

HAT-POUNCING MACHINE.

SPECIFICATION forming part of Letters Patent No. 629,190, dated July 18, 1899.

Application filed March 2, 1898. Serial No. 672,223. (No model.)

To all whom it may concern:

Be it known that I, WILLIAM H. JACKSON, a citizen of the United States, and a resident of Fall River, in the county of Bristol and State of Massachusetts, have invented certain new and useful Improvements in Hat-Pouncing Machines, of which the following is a specification.

This invention relates to new and useful improvements in hat pouncing or finishing machines, and has particular reference to brim-pouncers.

It is the object of my invention to simplify and generally improve the construction of machines of the above class, and particularly to provide an inexpensive device which is light running and easily operated.

With the above objects in view I have devised the simple and novel construction shown in the accompanying drawings, forming a part of this specification, upon which similar characters of reference denote like or corresponding parts upon the several figures, and of which—

Figure 1 is a plan view of my machine complete and containing a hat-body therein. Fig. 2 is a front view of the construction shown in Fig. 1, the hat being omitted. Fig. 3 is a longitudinal section on line *a a* of Fig. 1. Fig. 4 is a vertical cross-section on line *b b* of Fig. 1. Fig. 5 is an enlarged detail cross-sectional view of the pouncing-pad.

Referring to the characters of reference marked upon the drawings, 1 indicates the bed, which may be provided with legs or other suitable supports. (Not shown.) Upon this bed is mounted bearings 2, 2, in which are journaled shafts 3 and 4, the latter being a driving-shaft, through which power is conveyed to the machine. Gears 5 and 6 serve to form the necessary operating connection between said shafts, whereby one is operated by the other. I further provide upon the bed posts 7, which serve to support guide-rods 8 and 9, bearing reciprocating plates 10 and 11, containing pouncing-pads 12. The plates 10 and 11, together with their pads, are designed to be reciprocated back and forth upon the guide-rods by means of link connections 13 and 14 with cranks of the shafts 3 and 4, respectively. The shafts above

mentioned are operated at a high rate of speed, and consequently impart rapid reciprocal movement to the plates in question. The guide-rods 9 are mounted directly beneath the fixed rods 8 and, as will be apparent, serve to yieldably support the lower plate 11 by reason of the following mechanism: The posts 7 are cut away, as at 14^a, forming a reduced portion, upon which is mounted a spiral spring 15, one end of which abuts against a shoulder of the post and the other against and supports the free ends of the guide-rods 9.

The inner end of the plates 10 and 11 terminate in heads or pads 12, as shown, each of which are provided with clamps for holding sandpaper or similar material thereto. These clamps consist of a yoke 16, fitted in suitable ways of the plate, and bear engaging ends 17, as shown. This yoke clamps the paper beneath its ends 17 by means of a cam-lever 18, pivoted to said yoke and operating against the back of the pad, as shown in Fig. 5, and from which it will be obvious that the clamps are operated by the action of the lever.

To the outer end of the shaft 4 is attached pulleys 19 and 20, the former being provided with a belt connection 21 to a similar pulley on a top feed-shaft 22, while the latter pulley 20 contains a similar connection 23 with a top brush-shaft 24. Immediately below both the feed and brush shafts 22 and 24 are arranged corresponding shafts 22^a and 24^a, which are provided with pulley and belt connections to the shaft 3 similar to those of the top shafts and serve to drive the top and bottom shafts in opposite directions.

The feeding device consists of a pair of shafts 22 and 22^a, driven as above described and journaled in bearings 25, secured to the bed. The inner ends of these shafts are provided with knuckle-joints connecting them with short angular shafts 26, bearing feed-rollers 27 and 27^a, said angular shafts being 95 also journaled in bearings 28, attached to the main bed of the machine.

My machine is also provided with a pair of brushes, which serve to remove the dirt and dust from the hat-brim as the same is rotated and fed to its work. This cleaning device consists of shafts 24 and 24^a, journaled in

bearings 29, secured to the bed in a similar manner to those of the feeding mechanism. A pair of short shafts 30 and 30^a are connected to the above shafts by means of knuckle-joints 31, as shown, and are journaled in bearings 32. Upon the free ends of these shafts are secured brushes 33, which operate in conjunction with each other and serve to remove the fibers cut off by the action of the sandpaper. Beneath and to the guide-rod 9 is fixed a yoke 34, which straddles the lower plate and is connected in its center by means of an operating-lever 35, pivoted to the bed, as shown. (See Fig. 2.)

15 To the bed of the machine is attached a retaining-spring 36, over which the crown of a hat is placed where desired to operate upon its brim, which device serves to retain the hat in place during the operation thereon. From 20 the construction and illustration shown it will be seen that a hat is supported upon the machine by means of the feed-rolls, brushes, and the spring aforesaid, which latter serves as a guide to retain the brim between the 25 pads during their action.

The operation of my machine is as follows: The operator places one hand upon the lever 35 in a manner to lower the under pad and its connections, whereupon the brim is inserted between the two pads, and at the same 30 time the guide 36 is slipped into the crown in a manner to retain the same snugly against the ends of the pads. The brim is also worked in between both the brushes and feed-rolls, 35 after which the lever is released, allowing the under pad to come up into place to engage the hat-brim. The hat is caused to rotate upon an imaginary pivot as many times as may be necessary to complete its operation, 40 after which it is released by the action of the lever aforesaid.

Having thus described my invention, what I claim, and desire to secure by Letters Patent, is—

45 1. In a hat-brim-pouncing machine the com-

bination with driving-shafts, each having a crank, of guide-rods adjacent thereto, reciprocating plates mounted on said rods, pouncing-pads carried by said plates, links connecting said plates and cranks, rolls for feeding the hat-brim to the pads, a guide to retain the hat-brim in place, springs to operate against the under side of the lower rods, treadle connections with said spring-actuated guide-rod whereby it is lowered to insert a 55 hat-brim between the pads, substantially as described.

2. A hat-brim-pouncing machine comprising a bed, driving-shafts, each having a crank mounted thereon, posts secured to said bed, fixed and movable guide-rods secured to said posts, reciprocating plates mounted on said rods, pads supported on said plates, links connecting said plates to the crank-shafts aforesaid, treadle connections with said movable 65 guide-rod for separating the pouncing-pad, substantially as described.

3. A hat-brim-pouncing machine comprising in combination a bed, driving-shafts mounted thereon, posts attached to said bed, fixed and movable guide-rods secured on said posts, pouncing-pad plates slidably mounted on the rods, link connections between the cranks of the driving-shafts and the plates, springs operating against the movable guide-rod to normally hold its pad against that of the fixed guide-rods, treadle connections for operating said guide-rod to separate the pads, feed-shafts mounted in the bed, operated from the driving-shafts and bearing feed-rolls, 80 brush-shafts mounted adjacent to said feed-shafts and bearing-brushes to operate upon the brim of a hat, substantially as described.

Signed at Fall River, in the county of Bristol and State of Massachusetts, this 13th day 85 of January, A. D. 1898.

WILLIAM H. JACKSON.
